(57) **CLAIM**

The ornamental design for screen receiver prongs as shown and described.

DESCRIPTION

FIG. 1 is a perspective view of screen receiver prongs showing my new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines shown in the drawing figures illustrate a screen track and a magnet channel, which are elements of the article of manufacture that form no part of Applicant's claimed invention.
